(57) **CLAIM**

I claim the ornamental design for a magnet-embedded bracelet, as shown and described.

DESCRIPTION

FIG. 1 is a perspective view of a first embodiment of magnet-embedded bracelet of my new design.

FIG. 2 is a front view of a magnet-embedded bracelet or the like showing the preferred embodiment of FIG. 1, wherein the rear and side views are identical.

FIG. 3 is a top plan view of a magnet-embedded bracelet or the like showing the preferred embodiment of FIG. 1, wherein the bottom view is identical.

FIG. 4 is a perspective view of a second embodiment of a magnet-embedded bracelet showing my new design.

FIG. 5 is a front view of a magnet-embedded bracelet or the like showing the preferred embodiment of FIG. 4, wherein the rear and side views are identical.

FIG. 6 is a top plan view of a magnet-embedded bracelet or the like showing the preferred embodiment of FIG. 3, wherein the bottom view is identical.

FIG. 7 is a perspective view of a third embodiment of a magnet-embedded bracelet showing my new design.

FIG. 8 is a front view of a magnet-embedded bracelet or the like showing the preferred embodiment of FIG. 7, wherein the rear and side views are identical; and,

FIG. 9 is a top plan view of a magnet-embedded bracelet or the like showing the preferred embodiment of FIG. 7, wherein the bottom view is identical.

A bracelet, band, or the like made of a transparent or translucent material, clear or colored, is embedded with two or more elongated members, which are opaque or a contrasting translucent color, that extend radially around the bracelet and are visible through the material. Preferably the elongated members are magnets that are cylindrical and oriented as shown.
